UNITED STATES PATENT OFFICE.

HUGH M. MATHIESON, OF GLASGOW, SCOTLAND.

SCORE-INDICATING DEVICE FOR GAMES.

Application filed June 22, 1923. Serial No. 570,134.

To all whom it may concern:

Be it known that I, HUGH MILLER MATHIESON, a subject of the King of the United Kingdom of Great Britain and Ireland, 5 and residing at Glasgow, Scotland, have invented a certain new and useful Improvement in Score-Indicating Devices for Games, of which the following is a specification.

10 This invention relates to score indicating devices for games including a figured dial and slotted pointing means rotatably mounted on said dial adapted to be brought into register with figures printed thereon.

15 According to the invention the pointing means comprises arms of resilient material pivotally attached to and embracing the dial, the outer ends of the pointer being hingedly connected and presenting finger

20 grips associated with a spring compressible by hand and normally acting to maintain the inner surfaces of the arms in frictional engagement with the dial.

25 In the accompanying drawing Fig. 1 is a plane of one form, Fig. 2 an elevation of Fig. 1, Fig. 3 a section on the line A—A of Fig. 1 showing the fingers depressed. Fig. 4 is a plan of a second form and Fig. 5 a plan of a third form.

30 The score indicating device comprises a dial 1 whereon are rotatably mounted a pointer 2 or as in Fig. 4 pointers 2, 2^a. Each pointer is provided with a slot or slots (Fig. 5) arranged opposite a row of figures (Figs. 1 to 4) or rows of figures (Fig. 5) and adapted to register one at a time with a figure on the row or each row and each pointer is

provided with means for clamping the pointer or pointers to the dial 1.

Each pointer comprises two arms of resilient material pivotally attached at 3 to and arranged in juxtaposed relationship with the dial 1. The outer ends of the pointers are hingedly connected at 4 and are provided with finger grips 5 associated with a spring 6 normally acting to maintain the inner surfaces of the arms in frictional engagement with the dial 1. The arrangement is such that, when the finger grips 5 are depressed, the pointer may be moved over the dial until the slot or slots registers or register with the selected figure whereupon the finger grips are released and the pointer is held frictionally in adjusted position.

55 I claim:—

A score indicating device comprising a figured dial, slotted pointing means rotatably mounted on said dial, said pointing means comprising resilient arms embracing said dial, said arms hingedly connected at their outer ends and presenting finger grips and a spring compressible by actuation of the finger grips, said spring normally acting to maintain the inner faces of said arms in frictional engagement with said dial.

60 In testimony whereof I have signed my name to this specification in the presence of two subscribing witnesses.

H. M. MATHIESON.
